UNITED STATES PATENT OFFICE.

OAKLEY S. WALKER, OF WORCESTER, MASSACHUSETTS.

GRINDING-MACHINE.

1,091,407.

Specification of Letters Patent. Patented Mar. 24, 1914.

Application filed November 29, 1909. Serial No. 530,290.

To all whom it may concern:

Be it known that I, OAKLEY S. WALKER, a citizen of the United States, residing at Worcester, in the county of Worcester and 5 Commonwealth of Massachusetts, have invented a new and useful Improvement in Grinding-Machines, of which the following is a specification, accompanied by drawings forming a part of the same, in which—

10 Figure 1 represents a side elevation of a grinding machine embodying my present invention. Fig. 2 is a central, vertical, sectional view. Fig. 3 is a plan view of a system of speed reducing gearing between the 15 grinding wheel and the work supporting table. Fig. 4 is a side elevation of the vertically sliding head supporting the abrading wheel, and shown in its raised position. Fig. 5 is a plan view of the work supporting 20 table showing the position of the abrading wheel relative thereto, and Fig. 6 is a sectional view on a larger scale of the annular rim inclosing the work supporting table.

Similar reference characters refer to similar parts in the different views.

My present invention relates particularly to that class of grinding machines in which the work supporting table comprises a magnetic chuck for holding the work in proper 30 position while it is being subjected to the action of a revolving abrading wheel, and it has for its objects to facilitate the adjustment and manipulation of the machine, and to render certain operations automatic, and 35 these objects, among others, hereinafter pointed out, are accomplished by the construction and arrangement of parts as hereinafter described and set forth in the annexed claims.

40 Referring to the accompanying drawings 1 denotes a hollow supporting stand or framework upon which the operative parts of the machine are mounted, 2 is a driving shaft journaled in the base of the machine 45 and provided with tight and loose pulleys 3 and 4. The driving shaft 2 carries within the stand 1 a pulley 5 having a belt connection with a pulley 6 upon a vertical shaft 7. To the upper end of the vertical shaft 7 50 is attached a pulley 8 having a belt connection with a pulley 9, attached to a vertical grinding wheel shaft 10 journaled in a head 11, said head having a sliding movement in

vertical ways 12, by means of a rack and pinion mechanism comprising a rack 13 and 55 pinion 14 carried upon a spindle 15 projecting through the head 11 and provided on its outer end with a lever handle 16, thereby enabling the head 11 to be raised and lowered by the operator.

60 The lower end of the shaft 10 carries an abrading wheel 17 which is moved toward and away from the work 18 held upon a rotating work supporting table 19. The work supporting table 19 is carried upon the 65 upper end of a shaft 20 which carries a belt pulley 21 having a belt connection with a pulley 22, attached to a vertical spindle 23, having a geared connection with the vertical shaft 7 through a system of speed reducing gears, comprising the gears 24, 25, 26, 27, 28, 29 and 30, shown in plan view in Fig. 3, causing a slow rotative movement to be imparted to the work supporting table. The shaft 20 is journaled in a sliding bracket 75 31 capable of a vertical sliding movement in ways 32 and supported at any desired elevation by means of a screw 33 journaled in the bracket 31 and engaging a nut 34 held from rotation in a step 35. The screw 33 is 80 connected by gears 36 and 37 with a short spindle 38 having its outer end 39 polygonal to receive a wrench or crank handle by which the screw 33 may be rotated in order to raise or lower the work supporting table. 85

The work supporting table in the present instance comprises a magnetic chuck 40 of the usual and well known form of construction with its face forming the work supporting table 19. The magnetic chuck has an 90 electrical connection through the brushes 41 and 42 with an electrical switch 43 mounted on the side of the upright stand or framework 1. The switch is provided with a pair of contact surfaces 44 and 45 adapted to contact with a vertically moving switch bar 46 carried by the sliding head 11, whereby there is completed an electric circuit by which the magnetic chuck is energized whenever the sliding head 11 is depressed for the purpose 100 of bringing the abrading wheel 17 into contact with the work. When the sliding head 11 is raised to its highest position as shown in Fig. 4, the switch bar 46 is removed from the contact surfaces 44 and 45 and passed 105 completely across a second pair of contact

surfaces 44 and 48 connected by crossed wires with the poles of the magnetic chuck, whereby the polarity of the chuck is reversed as the switch bar 46 passes over and in contact with the surfaces 44 and 48.

The contact surfaces 47 and 48 are made of such length that at the usual and convenient speed of raising the head 11 the reversal of the electric current will be continued for just the length of time required to completely demagnetize the magnetic chuck. The magnetic chuck will therefore be energized by two electrical currents of opposite polarities at each upward or downward movement of the head 11. When the head 11 is moved down the magnetic chuck will become energized by the passage of the switch bar 46 over the contact surfaces 47 and 48. The continued downward movement of the head 11 will carry the switch bar 46 across the gap between the upper and lower pairs of contact surfaces and into permanent contact with the lower pair of contact surfaces 44 and 48. The contact of the switch bar with the lower pair of contact surfaces first destroys the magnetism already imparted to the chuck by the passage of the switch bar over the upper pair of contact surfaces, but as the contact remains permanent the chuck becomes again magnetized, with the polarity determined by the lower pair of contact surfaces which is the reverse of the polarity set up by the first pair of contact surfaces.

The head 11 is counterbalanced by the weight 49 connected with the head 11 by a cable 50 passing over a pulley 51. The downward movement of the head 11 along the ways 12 is limited by a stop 52 adjustably attached to the supporting stand 1. When the head 11 is raised to carry the abrading wheel 17 out of operative position upon the work, the rotation of the work supporting table 19 is stopped automatically by means of a rocking lever 53 pivoted at 54 upon the side of the stand, and having one end slotted to engage a pin 55 carried by the sliding head 11. The opposite end of the rocking lever 53 is pivotally connected by a link 56 with a second rocking lever 57 attached to a rocking shaft 58, which carries a bifurcated arm 59 provided with slotted ends which engage pins 60 projecting from the sides of a collar 61 upon which the pulley 22 rests. The lower end of the pulley 22 is provided with a clutch member 62 which, as the pulley is allowed to fall, engages a similar clutch collar 63 attached to the spindle 23 causing a rotation of the pulley 22. The raising of the head 11, however, rocks the shaft 58 through the connecting mechanism already described to lift the collar 61 and raise the pulley 22 to carry its clutch member 62 out of engage-

ment with the clutch collar 63, thereby checking the rotation of the work supporting table. Attached to the sliding bracket 31 is a shelf 64 upon which is mounted a rotating fan blower 65 driven by a motor 66, for the purpose of forcing a current of air upward through the hollow shaft 20 into the interior of the chuck 40 from which it escapes through openings 67, 67.

The work supporting table 19 is cylindrical and is provided with a projecting flange 75 68, upon which is supported an annular rim 69 having a depending flange 70, which overlaps an internal annular flange 71 projecting upward from the bottom of a cup shaped case 72 which incloses the rotating work supporting table. Water is directed through a spout 73 upon the work held upon the work supporting table. The water fed to the work supporting table is caught at the bottom of the cup shaped case 72 and removed through a pipe 74, the flanges 70 and 71 preventing the access of water to the brushes 41 and 42 and also to the bearing of the shaft 20.

The operation of my improved grinding machine is as follows: Power is applied from the driving shaft 2 to the vertical shaft 7 from which a rapid rotary motion is imparted by the pulleys 8 and 9 to the abrading wheel shaft 10 and abrading wheel 17. Rotary motion is imparted through the system of reducing gears shown in plan view in Fig. 3, from the shaft 7 to the spindle 23. The head 11 is raised in the position shown in Fig. 4 providing space 100 between the abrading wheel 17 and the surface of the work supporting table for the arrangement of work on the latter. The work 18 is then placed upon the surface of the work supporting table as shown in Fig. 105 5, while the table is in a state of rest. The sliding head 11 is then lowered by means of the lever handle 16 until it strikes the work 18. During the downward motion of the head 11 the magnetic chuck 40 becomes energized by the contact of the switch bar 46 with the lower pair of contact surfaces 44 and 48. The depression of the sliding head 11 lowers the pulley 22 until its clutch member 62 engages the clutch collar 63 which is attached to the spindle 23, causing a rotary motion to be imparted to the work supporting table through the belt pulleys 21 and 22. The rotation of the work supporting table carries the pieces of work 18 successively beneath the lower surface of the abrading wheel 17 which is preferably cup shaped. As the grinding is continued the sliding head 11 is permitted to descend until it reaches the fixed stop 52 which checks its downward movement and determines the thickness of the finished work. The sliding head 11 is then raised, causing the pulley

22 to become disconnected from its driving spindle 23, again checking the rotation of the work supporting table. The upward movement of the sliding head 11 also carries the switch bar 46 out of contact with the surfaces 44 and 45 and moves the switch bar across and in contact with the upper pair of contact surfaces 47 and 48, which by crossed wires reverse the polarity of the 5 magnetic chuck, thereby demagnetizing the chuck and allowing the work to be removed. The length of the contact surfaces 47 and 48 is sufficient to allow the contact to be maintained between them and the switch 10 bar 46 a sufficient length of time at the speed at which the sliding head is moved upwardly to just effect the demagnetizing of the chuck.

A variation in the thickness of the work 20 ground may be accomplished by varying the position of the stop 52 or by raising or lowering the bracket 31 in which the work supporting table is journaled. The annular rim 69, a portion of which is shown on a 25 larger scale in Fig. 6, is adjustably supported on the projecting flange 68 by means of screws 75 carried by the rim 69, with their tips resting upon the flange 68, thereby enabling the rim 69 to be raised above the horizontal plane of the face of the work supporting table 19 in order to form an annular rim to prevent the sidewise removal of work from the work supporting table. The use of the fan blower 65 causes a current of air to 30 pass through the interior of the magnetic chuck and prevents an accumulation of moisture therein. The fan 65, in the present instance, is driven independently by the motor 66, but it might obviously be connected through a belt connection with a driving pulley upon one of the rotating shafts by such a connection as would permit the up and down movement of the fan, or the fan might be held in a fixed position and be connected with the hollow shaft 20 of the magnetic chuck by a flexible connection.

All the operations of the machine are automatically performed with the exception of raising and lowering the abrading wheel, 35 placing the work upon the work supporting table and removing it therefrom. Each rising movement of the head 11 withdraws the abrading wheel from the work, automatically stops the rotation of the work supporting table, and demagnetizes the chuck 40, while the downward movement of the head 11 brings the abrading wheel into operative position, causing a downward movement of the wheel, as the thickness of the 45 work is reduced until the descent of the head 11 is checked by the stop 52. Simultaneously with the downward movement of the head 11 the magnetic chuck becomes energized through the automatic switching mech-

anism and the work supporting table is started and caused to slowly rotate in order to carry the pieces of work successively beneath and in contact with the abrading wheel.

To place the work in position and automatically grind the same to any predetermined thickness only requires the raising and lowering of the abrading wheel, allowing the entire surface of the work supporting table to be covered with pieces of work, 75 as the periphery of the abrading wheel overlaps the center of the rotating work supporting table. As the abrading wheel 17 is cup shaped the grinding operation is confined to the narrow surface forming the side of 80 the wheel rim, so that the speed of the grinding surface of the wheel in contact with the work is substantially uniform.

I claim,

1. In a grinding machine, a work supporting table having an outwardly extending flange with a rim depending therefrom, a casing surrounding said table, means for admitting water upon the work held on said table, a shaft supporting said table and passing through said casing, and means carried by said casing and projecting into the space between said table and said depending rim, for preventing access of water to said shaft.

2. In a grinding machine, a rotatable work supporting table, a grinding wheel in operative relation to said table, means for raising and lowering said grinding wheel, and an automatic attachment between said grinding wheel and said rotatable table arranged 95 to stop the rotation of said table when said wheel is raised, and to start the rotation of said table when said wheel is lowered into operative position.

3. In a grinding machine, a bracket vertically slidable in ways in the framework of the machine, a shaft journaled in said bracket, a work supporting table secured to the upper end of said shaft, means for rotating said shaft, and means for adjusting 105 said bracket vertically.

4. In a grinding machine, a fixed framework having vertical ways, a head slidable on said ways, a shaft journaled in said head, a grinding wheel carried by said shaft, vertical ways in said framework below said grinding wheel, a bracket vertically adjustable in said lower ways, a shaft journaled in said bracket with its axis parallel with the axis of said grinding wheel, a work 115 holding table carried by said shaft and means for rotating said shaft.

5. In a grinding machine, work supporting means having an interior chamber, a shaft secured to said work supporting means, 120 having a bore in communication with said chamber, and means for forcing air through the bore of said shaft into said chamber.

6. In a grinding machine, a fixed framework having vertical ways, a bracket vertically adjustable in said ways, a hollow shaft journaled in said bracket, a work holding hollow table carried by said shaft, and a fan also vertically adjustable with said bracket arranged to cause a current of air to pass through said hollow shaft and enter said hollow table.
- 10 7. In a grinding machine, a framework having a vertical way, a bracket sliding in said way, means for vertically adjusting said bracket, a shaft journaled in said bracket, a rotatable work holding table carried by said shaft, a rotatable grinding wheel above said table having its axis parallel with but eccentric to the axis of said table, said grinding wheel having its working face in overlapping relation to the axis of said table.
- 15 8. In a grinding machine, a fixed framework having vertical ways, a bracket slideable on said ways, means for vertically adjusting said bracket, a hollow shaft journaled in said bracket, a work holding table carried by said hollow shaft, a magnetic chuck inclosed in said table, and means vertically movable with said bracket for forcing air through said hollow shaft to said magnetic chuck.
- 20 9. In a grinding machine, a fixed framework, a rotatable work holding table, a rotatable grinding wheel, means for moving said grinding wheel toward and away from said table, and means for automatically controlling the rotation of said table by the movement of said grinding wheel toward and away from said table.
- 25 10. In a grinding machine, a rotatable work holding table, a shaft operatively connected with said table through a clutch mechanism, a slideable head, a grinding wheel carried by said head, and means for engaging and disengaging said clutch mechanism by the movement of said slideable head.
- 30 11. In a grinding machine, a rotatable work holding table, comprising a magnetic chuck included in an electric circuit, a grinding wheel, means for moving said grinding wheel toward and away from said table, and an electric switch operatively controlled by the movement of said grinding wheel toward and away from said table.
- 35 12. In a grinding machine, a rotatable work holding table, comprising a magnetic chuck included in an electric circuit, a switch for the electric circuit, a rotatable grinding wheel having its axis parallel with and eccentric to the axis of said rotatable table, means for varying the distance between said table and said grinding wheel and for controlling said switch corresponding to the relative positions of said table and said grinding wheel.
- 40 13. In a grinding machine, a fixed framework, a rotatable work holding table, comprising a magnetic chuck included in an electric circuit, a head slideable on said framework, a grinding wheel carried by said head, means for moving said head to carry the grinding wheel toward and away from said table, and an electric switch, comprising contact surfaces held on the fixed framework and a switch bar having opposing contact surfaces carried by said sliding head.
- 45 14. In a grinding machine, a work holding table comprising a magnetic chuck, a grinding wheel, means for moving said wheel toward and away from said table, an electric switch for said chuck, said switch having contact surfaces arranged to energize said chuck by electrical currents of opposite polarities, and means for completing an electric circuit through each pair of contact surfaces by the movement of said grinding wheel in each direction.
- 50 15. In a grinding machine, a movable work supporting table, a rotatable grinding wheel, means for moving said grinding wheel into and out of operative position with respect to said table, and means, actuated by said first mentioned means, for starting the movement of said table, when said wheel is moved into its operative position.
- 55 16. In a grinding machine, a movable work supporting table, a rotatable grinding wheel, means for moving said grinding wheel into and out of operative position with respect to said table, and means, actuated by said first mentioned means, for stopping the movement of said table, when said wheel is moved into its inoperative position.
- 60 17. In a grinding machine, a movable work supporting table, a grinding wheel adapted to operate upon work supported by said table, means for moving said grinding wheel toward and away from said table, and means for controlling the movement of said table by the movement of said grinding wheel toward, and away from said table.
- 65 18. In a grinding machine, a rotating shaft, a rotatable work supporting table, a clutch mechanism adapted to operatively connect said shaft with said table, a grinding wheel rotated by said shaft and adapted to be shifted toward and away from said table, and means for engaging and disengaging said clutch mechanism by the shifting of said grinding wheel.
- 70 19. In a grinding machine, a magnetic work retaining means included in an electric circuit, a grinding device adapted to be shifted toward and away from said work retaining means, and means operated by the shifting of said grinding device for opening and closing said electric circuit.
- 75 20. In a grinding machine, means adapted

to hold and support the work, grinding means, means for shifting said grinding means into and out of operative position with respect to said work holding means, and means, operated by said shifting means for rendering said work holding means active or inactive.

21. In a grinding machine, means for holding the work, grinding means, means for shifting said grinding means into operative position with respect to the work, and means, actuated by said shifting means, for rendering said work holding means active.

22. In a grinding machine, means for holding the work, grinding means, means for shifting said grinding means out of operative position with respect to the work and means, actuated by said shifting means, for rendering said work holding means inactive.

23. In a grinding machine, means for holding the work, grinding means, means for shifting said work holding means and said grinding means into and out of operative position with respect to each other, and means, actuated by said shifting means, for rendering said work holding means active or inactive.

24. In a grinding machine, movable means for holding the work, grinding means, means for shifting said work holding means and said grinding means into and out of operative position with respect to each other, and means, actuated by said shifting means, for starting and stopping the movement of said work holding means.

25. In a grinding machine, a rotatable work supporting means, a grinding means, means for shifting said work supporting means and said grinding means into and out of operative position with respect to each other, and means actuated by said shifting means for starting and stopping the rotation of said work supporting means.

26. In a grinding machine, a movable work supporting means, grinding means, means for shifting said work supporting means and said grinding means into and out of operative position with respect to each other, means, actuated by said shifting means, for starting and stopping the movement of said work supporting means, and means, also actuated by said shifting means, for rendering said work holding means active or inactive.

27. In a grinding machine, a rotating shaft, a rotatable work supporting table, a clutch mechanism adapted to operatively connect said shaft with said table, a grinding wheel rotated by said shaft, means for shifting said grinding wheel and said table into and out of operative position with respect to each other, and means, actuated by said shifting means, for engaging and disengaging said clutch mechanism.

28. In a grinding machine, a magnetic work retaining means included in an electric circuit, a grinding means, means for shifting said grinding means and said work retaining means into and out of operative position with respect to each other, and means, operated by said shifting means, for opening and closing said electric circuit.

29. In a grinding machine, a work supporting table comprising a magnetic chuck included in an electrical circuit, a switch in said circuit, a grinding wheel, means for shifting said grinding wheel and said table into and out of operative position with respect to each other, whereby the switch is operated to close and open said electrical circuit.

30. In a grinding machine, a fixed framework, a work supporting table, comprising a magnetic chuck included in an electrical circuit, a head slideable in said framework, a grinding wheel carried by said head, means for moving said head to carry the grinding wheel toward and away from said table, a reversing switch in said electrical circuit, and means carried by said head for closing and opening said switch to energize and de-energize said chuck upon movement of said head.

31. In a grinding machine, a work supporting table, comprising a magnetic chuck included in an electrical circuit, a grinding wheel, means for shifting said grinding wheel into operative position with respect to said table, and means, actuated by said shifting means, adapted to close said electrical circuit and thereby energize said magnetic chuck.

32. In a grinding machine, a work supporting table, comprising a magnetic chuck included in an electrical circuit, a grinding wheel, means for shifting said grinding wheel out of operative position with respect to said table, and means, actuated by said shifting means, adapted to open said electrical circuit and thereby deenergize said magnetic chuck.

33. In a grinding machine, a work supporting table, comprising a magnetic chuck included in an electrical circuit, a grinding wheel, means for shifting said grinding wheel and said table into and out of operative position with respect to each other, and means, actuated by said shifting means, adapted to close and open said electrical circuit, and thereby energize and deenergize said chuck.

34. In a grinding machine, a work supporting table, comprising a magnetic chuck included in an electrical circuit, two pairs of contact pieces in said circuit in reversed relation, a grinding wheel, means for shifting said grinding wheel out of operative position with respect to said table, and

means carried by said shifting means and adapted to close said circuit through the contacts of one pair when the grinding wheel is in operative position, to energize said chuck, and adapted, when the said shifting means is operated, to break said circuit, and then form a circuit momentarily through

the other pair of contacts, and thereby demagnetize the said chuck.
